SLATTED BLIND

Robert C. Clark and Thomas C. Jones,
San Francisco, Calif.

Application October 28, 1947; Serial No. 782,500

4 Claims. (Cl. 160—172)

1

This invention relates to improvements in slatted blinds for windows, of a type commonly called Venetian blinds, and more particularly relates to such blinds in which slats are tiltable and readily removable and replaced, and guided in their upward and downward movement.

Disadvantages have heretofore been encountered in so-called Venetian blinds in maintaining the slats clean in use, in maintaining the slats in proper substantially parallel relation while being raised and lowered, in eliminating rubbing of the ends of slats against window draperies, in tilting the slats to a completely closed position, in making lifting cords invisible, in laundering the guiding supporting tapes, as well as other disadvantages.

Therefore, it may be stated as among the objects of this invention are to provide a Venetian blind apparatus in which the cords for raising and lowering the slats do not pass through the slats or any portion thereof; to provide easily removable and replaceable slats; to provide for easy and uniform raising of the slats and maintaining them relatively parallel; to provide means for guiding the vertical movement of the slats; to provide for maintaining the slat ends out of contact with window draperies; to provide for tilting the slats to closely overlying substantially contacting relation of their adjacent edges when the slats are tilted to closed position; to provide for making the elevating cords invisible; to provide for removability of the supporting tapes for laundering; to provide the foregoing advantages without radical departure from the standardized parts of such blinds, and to improve generally upon the economy of manufacture and efficiency of operation of devices of this character.

With the foregoing and other objects in view, all of which will more fully herein appear, one form in which the invention may be embodied is set forth in this description and illustrated in the accompanying drawing, it being understood that changes in form, size, degree, material and other minor details may be resorted to by substitution of equivalents, without departing from the spirit of the invention which is defined in the appended claims.

In the drawing:

Fig. 1 is a front elevational view, partly in section;

Fig. 2 is a top plan view, partly broken away;

Fig. 3 is a fragmentary longitudinal section on line 3—3 of Fig. 1;

Fig. 4 is a fragmentary longitudinal section on line 4—4 of Fig. 1;

2

Fig. 5 is a perspective enlargement of a portion of Fig. 1;

Fig. 6 is a fragmentary end view of a modified form, and

Fig. 7 is a vertical fragmentary section of tapes and slats illustrative partly of operation.

Referring to the drawing in which like reference characters indicate corresponding parts in the several views, 10 indicates generally a frame such as the usual window or door frame, in connection with which a slatted blind is to be hung. There is secured to and extending forwardly from the window frame a headplate 11 which is disposed in a horizontal plane of a length substantially equal to the width of the window frame opening. The specific means for securing the headplate to the window frame may be of any suitable type of bracket of sufficient strength, bearing in mind that at times there may be considerable stress of pull on the cords of the blind, and further bearing in mind that the blind must be adequately supported vertically as well as against lengthwise movement, and that the brackets must not interfere with the operation of raising, lowering, or tilting of the slats of the blind or the manipulation of operative cords. Supporting brackets of conventional type are here shown at 12 and 13. A canopy 14 may likewise be mounted by any suitable brackets over the top of the headplate, with a depending front board 14a, the canopy not being an operative element, but merely for esthetic appearance and to provide a means behind which the slats may be hidden from view when they are completely raised, as well as to prevent dust from settling on the headplate and also the slats when the latter remain in completely raised position over long periods of time.

Suspended from the under face of the headplate 11 is an upper tilting rail 15, one end of which is pivotally and removably mounted by pin 16 in an open hooked bracket 17, and the opposite end of which is pivotally and removably mounted by a square-headed pin 18 in a tilting gear assembly generally indicated 19. The tilting gear assembly is a standard and conventional assembly obtainable in several types on the open market and therefore is not described or illustrated in detail of its parts, other than to state generally that one well-known type which is adapted for use has a casing provided with a bracket for mounting it to the headplate, and within the casing is a driven worm shaft with which meshes a driven worm gear having a square axial opening to receive the square end of

pin 18, the worm shaft having mounted at one of its ends outside of the casing a small sheave, the groove of which has sockets therein and which may be rotated in either direction by a chain 20 of successively linked balls. Thus, when either end of the chain is pulled it rotates the sheave and thereby the worm drive shaft and the driven worm gear and the pin 18, whereby the upper tilting rail 15 may be tilted from a horizontal plane.

Upon the upper tilting rail are securely mounted one end of relatively longitudinally spaced textile web tapes 21 forming elongated depending loops, of which there are always at least two, and more if appropriately necessary for a wider blind. Secured to and preferably enclosed within the opposite end of the opposed flights of the loop of the web tapes so as to be tiltable thereby, is a lower tilting rail 22 which is likewise secured to the tape so that the upper and lower tilting rails may be tilted in unison. Any suitable means may be employed to secure the tapes to the upper and lower tilting rails, such as staples, but it is preferred that such securing means be releasable snap fasteners or buttons 23, since this type of fastener permits the tapes to be readily removed from the tilting rails for laundering or replacement.

The opposite ends of the lower tilting rail are pivotally mounted by pins 24 in slide blocks or shoes 25, 25a, which ride in opposingly spaced channels 26 and are slidably confined therein by flanges 26a at the opposite edges of spaced vertical side wings 27. These side wings are of somewhat greater vertical height than the entire length of the tapes 21. In order to reduce frictional drag, the slide blocks 25 have a portion of their opposite sliding faces cut away as at 28 so that they have sliding bearing on rounded end portions only. At least one of the side wings is hingedly mounted by any suitable type of hinge member 29, it being optional whether the opposing wing be hingedly mounted, though under certain conditions it is desirable to have both wings hingedly mounted, in order to meet conditions where one end of the blind must be positioned so closely to a wall or other obstruction that a wing at that end could not be swung outward on its hinges, in which event the opposite hinged wing would be available for the use and purposes hereinafter described. For usual installations, however, it is believed that having one end wing hingedly mounted is sufficient.

It will be observed that the tape loops 21 are provided with vertically spaced cross webs or lacing webs 30 connecting the opposite flights or runs of the tape loop, forming what may be termed a tape ladder. These cross webs support elongated slats 31, the relative vertical spacing of the cross webs being just a trifle less than the lateral transverse width of the slats. The slats are of wood, plastic, or lightweight sheet metal strip material, and are rectangular in plan so that they may be cut from strip material perpendicular to the longitudinal edges of the strip, and are free of holes, notches, or other accommodations for passing cords therethrough or attachment of cords thereto. They are of sufficient width so that when tilted by the tape ladder from a normal horizontal plane to a substantially vertical plane, they relatively overlap slightly at their adjacent edges, that is, the lower edge of one tilted slat slightly overlaps the upper edge of the next adjacent slat when the slats 75

are completely tilted to vertical positions. The slats rest loosely upon the cross webs 30, and are of sufficient length so that their ends loosely and slidably engage within the channels 26 of the opposed side wings, so as to be guided and aligned thereby in upward and downward movement.

Cord means are provided for raising and lowering the tapes and slat ladder, consisting of a cord loop 32 for manual manipulation, the loop being divided into two branches or lines which move in unison by means of a clasp 33. Both branch lines pass through a small sheave 34 having a helical thread at the bottom of its groove so that the cords run free at the center of the groove and by pulling the cord loop laterally the branch line cords are thrown against a braking or locking surface. This sheave and cord arrangement are well-known standard equipment in this art and need no more detailed description. One branch line cord 35 runs from the sheave 34 over a small guide pulley 37, then back of the channel flange or front molding 26a and forwardly of the adjacent end of the slat ladder, and has its terminal end removably attached to the forward portion of the upper edge of the slide block 25 by a snap hook 35a, whereas the other cord line 36 extends from the sheave 34 diagonally across the upper face of the headplate 11, thence over an antifriction small guide pulley 37a and downwardly behind the adjacent opposite end portions of the slat ladder, and has its terminal end removably attached to the rearward upper edge portion of the slide block 25a by similar snap hook 36a. Suitable upstanding spacer blocks 38 which may also serve as guides, may be provided on the upper face of the headplate 11 so that the canopy will not contact the cord 36 and restrict its free movement.

In the modification of Fig. 6 the side wings 27a are not hingedly mounted to swing as in Fig. 1, but the slats are removable and replaceable through a vertical slotted opening 27b in the side wing, the slot being preferably of lesser width than the lateral transverse width of the slats. The slats may be removed through this elongated slotted opening by tilting the slats from their normal horizontal plane to a partially vertical plane, though when the slats are in their normal horizontal plane position they will not slide through the opening because the slot is narrower than the width of the slat.

In operation the raising and lowering of the slats is accomplished by pull and release manipulation of cord loop 32, and the lines thereof 35, 36, the line 35 being hidden from view behind the wing flange 26a at one end of the blind and the line 36 being hidden from view behind the opposite ends of the slats, both lines sliding freely because they are held away from frictional contact with the slats; inasmuch as the small guide pulleys 37, 37a, as the case may be, are positioned at the edge portion of the headplate and have the terminal ends thereof secured to the outer ends of the upper edge of the slide blocks. Since these latter attachments are releasable, they permit the upper and lower tilting rails 11, 22, to be entirely separated from the elevating cord arrangement and removed as a unit, such removal being accomplished by lifting the pin 16 from the upper tilting rail bracket 17 and removing the opposite square bead pin 18 from the square axial opening of the driven gear of tilting apparatus 19.

In the apparatus of Fig. 1 it is only necessary

to swing one of the hinged wings 27 outwardly and to detach the snap hooks of cords 35, 36 from the slide blocks, whereupon the upper and lower tilting rails, the slide blocks, the tape ladder, and the slats may be removed as a unit, for cleaning or repair, or the individual slats may be removed as desired. In the modification of Fig. 6 which does not have the hinged mounting of the side wings, the slats should first be removed through the slotted opening 27b, said snap hooks released, and then the lower tilting rail 22 and the attached slide blocks may be removed or replaced between the wings by tipping to an inclined position. When thus dismounted, the tapes may be removed by unsnapping the snap fastener buttons so that the tapes may be laundered. If the tapes are stapled to the tilting rails it is only necessary to remove a few staples which makes laundering equally and easily practical.

In raising and lowering the slats it is to be noted that the slide blocks and the ends of the slats are guided by the channels 26 so that the slats are maintained vertically aligned, and that the weight of the lower tilting rail, guided as it is by the slide blocks 25, maintains the slots in relative parallelism while they are being raised and lowered. In this connection it will be also observed that the clasp 33 on both lines of the pull cord 32 simultaneously or jointly makes the pull or release tension equal on both the elevating lines 35, 36.

As previously stated, the tilting of the slats from normal horizontal fully open position to a substantially vertical fully closed position, or to any intermediate position is accomplished by the tilting gear generally indicated 19, operating to tilt the upper tilting rail 11 and thereby tilting the crosswebs 30 of the tapes upon which the slats repose, and also tilting the lower tilting rail 22. Since the lower tilting rail is pivotally mounted by pins 24 in the slide blocks which are guided in channels 26, regardless of the angle of tilt of the slats and tilting rails, the operation of raising and lowering of the slats of the blind is with equal facility regardless of the angle or plane of the slats.

It is to be further noted that by providing that the respective elevating lines 35, 36 shall operate totally independent of, and free of any connection to the slats, the slats may be tilted to a substantially complete vertical position, the cross webs of the tape ladder being so spaced relatively that when the slats are tilted to a substantially complete vertical position the adjacent edges of next adjacent slats overlap just a trifle so that the blind is completely closed to light or vision therethrough. The advantage of this facility may be illustrated by comparison with the well-known method of threading the elevating cord lines through holes in the longitudinal center of the slats in line with and under-

lying the tapes, in which event the thickness of the cord lines prevents the slats from closing or remaining completely closed when tension is released on the lines.

Since in both raising and lowering the slats they are guided in the channels 26 of the wings, there is no possibility of rubbing or snagging against adjacent draperies around a window or other place where the blind is used. Also, by such guiding and retention of the ends of the slots and lower tilting rail in the guiding channels 26, there is no possibility for the flexibly tape-supported blind to blow out into a room, if a window be open for ventilation.

Having thus described the invention, what is claimed as patentable is:

1. A slotted blind structure including a plurality of elongated slats, upper and lower tilting rails, flexible means interconnecting the slats and tilting rails, means for raising and lowering the lower tilting rail and slats, a guide channel at each side of the blind structure, a slide block freely slidable in each guide channel, pivotal connections between the slide blocks and the ends of the lower tilting rail, and hinge means for securing one guide channel to a window frame so that said channel can be readily swung to one side to facilitate removal of the tilting rails, slats and slide blocks.
2. The combination of claim 1, in which the slide blocks extend across the guide channels and the slide blocks have a portion of their opposite sliding faces cut away so that said blocks have sliding bearing on rounded corner portions, to reduce frictional drag.
3. The combination of claim 1 in which the slide blocks extend across the guide channels and the slide blocks have a portion of their opposite sliding faces cut away so that said blocks have sliding bearing on corner portions, to reduce frictional drag.
4. The combination of claim 1 including hinge means for securing each channel to a window frame so that both channels can be readily swung to the side to facilitate removal of the tilting rails, slats and slide blocks.
